SIGNAL DEVICE

Yukichi Iwata, Tokyo, Japan

Application August 16, 1954, Serial No. 450,000

2 Claims. (Cl. 102—37.8)

the signal device at the lower end portion thereof, a part of the device being broken away; Fig. 3 is a horizontal cross sectional view taken on the line III—III of Fig. 2; and Fig. 4 is a fragmentary sectional view of the bottom of the cylindrical tubular body shown in Fig. 2.

The cylindrical tube illustrated in Fig. 1 is a type of device wherein ignition is caused by rubbing materials such as, for example, a match stick head and ignition agent, against each other.

10 The material in the match head used herein may be composed of, for instance, S or Sb₂S₃ including a little potassium chlorate as an oxidizing agent, powdered glass to increase the friction and some glue to hold the mass together, and the abrasive agent may consist mainly of red phosphorus, Sb₂S₃, powdered glass to increase the friction and some glue.

On ignition, the red phosphorus is ignited with the aid of the potassium chlorate when the material in the head is struck upon the piece coated with the abrasive agent, whereby the combustible agent is ignited by means of the oxidizing agent.

15 In the drawings, 1 is a cylindrical body or housing containing the inflammable powder 2 in a storage chamber, the upper portion of the housing being hermetically sealed with a closing disc 3, and an ignition chamber 4 being provided inside of the upper portion of said cylindrical body. A supporting shaft 6 is vertically provided in a small inner tube 5 extending longitudinally through the central portion of a cylindrical portion or chamber B of the lower portion of the said chamber 4 containing the inflammable agent 2. The lower end portion of the supporting shaft 6 is loosely passed through the bottom plate 7 of a powder accommodating chamber, whereas a holder 9 holding the match stick head 8 is secured to the upper end portion of said shaft 6. Inside of the ignition chamber 4, a cylindrical coil spring 10 is attached at one end to the upper end face of the powder accommodating chamber B around the aforementioned supporting shaft 6 and a small cylindrical coil spring 11 is disposed above the upper part of said spring 10. A piece 12 coated with the abrasive agent is secured on the inner surface of said spring 11, and an ignition device A is composed of said piece 12 with the abrasive agent and the aforementioned holder 9 carrying the match stick head 8.

20 Further, it is an object of the invention generally to improve on signaling devices as now customarily built.

The present invention provides a signal device, which has been improved to overcome various defects involved in known types of signal devices, in which an ignition device is secured to the inside or outside portion of the upper end of a cylindrical body containing inflammable powder. A gripping portion is provided having a trigger at the lower portion thereof; and an operating rod, which is moved mechanically by the squeezing of the trigger manually, is arranged therein and extends through a cylindrical body longitudinally at the center, near the center or outside portion thereof. The ignition device or the whole of the ignition and operational devices are enclosed tightly in a water-proof, cylindrical covering body, wherein the ignition device may be caused to operate mechanically by the moving of the trigger and thereby the inflammable powder can be made to burn. The ignition may be performed electrically.

25 According to the present invention, when an accident suddenly occurs, for example, on a railroad, a smoke signal can be ejected readily by simply squeezing the trigger of the device at the scene of the accident, so that the following train may be promptly stopped whereby the protection of traffic as well as of the railroad itself is readily obtained. In such a case of emergency, the issuance of a danger signal is preferably without delay, and signal failure must absolutely be avoided independently of weather conditions.

30 According to the present invention, when an accident suddenly occurs, for example, on a railroad, a smoke signal can be ejected readily by simply squeezing the trigger of the device at the scene of the accident, so that the following train may be promptly stopped whereby the protection of traffic as well as of the railroad itself is readily obtained. In such a case of emergency, the issuance of a danger signal is preferably without delay, and signal failure must absolutely be avoided independently of weather conditions.

35 In addition to being a reliable device, the signal device of the present invention may be utilized extremely effectively as a signal lantern in the dark or for various other purposes.

40 The signal device of the present invention has a simple construction and is not only safe and easy to handle and operate, but also dispenses with the need for the removal of a cap-cover portion as is required in known signal devices.

45 In order that the present invention may be more clearly understood, the following description is given with reference to the accompanying drawing.

50 Figures 1 to 4 of the drawing represent embodiments of a tubular signal device in which the controlling bar of the controlling device extends longitudinally through the central hollow portion of a cylindrical body. Fig. 1 is a longitudinal sectional view of one embodiment; Fig. 2 is a front view of a modification wherein a rotatable inner tubular body envelopes the cylindrical body of

make the ignition signal with speed and reliability by the actuation of the trigger upon the occurrence of an emergency. 29 is a spike to be struck into the sleeper of the railway when the signal of the present invention is used.

In Figs. 2, 3 and 4, the upper-end opening of the cylindrical body 1 accommodating inflammable powder 2 is hermetically closed with a closing disc 3 such as shown in Fig. 1, and abrasive agent carrier 12 is attached on the top inner circumferential portion of a small inner tube 5 extending longitudinally through the inflammable powder accommodating chamber B. The holder 9 of the material of the head of the match stick is secured to the controlling rod 17 disposed longitudinally within the inner tube 5 in the vicinity of the upper end thereof and opposite to said abrasive agent holder 12. An ignition chamber A communicates with the abrasive-agent carrier 12 and the holder 9. In the closed chamber 75 at the lower end of the cylindrical body 1, the trigger body 24 loaded with a coil spring 23 is so provided that it may pivot on an axial center 25. Further, the central projected portion 26 of said trigger body 24 is connected with the bottom end portion of said controlling rod 6 which is guided by said inner tube 5. A window 27 is formed through the side portion of the sealed chamber 75 located at the lower end of the cylindrical body, to which window is pasted a sheet 28 of water proof paper or other water proof material. Thus, the outside and inside of the chamber are sealed in a water tight manner to prevent the penetration of moisture. A cover tube 30 is rotatably fitted outside of the lower sealed chamber 75 of the cylindrical body 1, and a window 31 is formed through the cover tube 30 in a position corresponding to the window 27 of the aforementioned sealed chamber so that the windows are in register with each other. Similarly, said window 31 is provided with a sheet of water proof paper 32 pasted thereon or with another suitable water proof material. Whenever needed, the two windows are placed opposite each other, and thereafter as both water proof papers are broken with the finger tip, the trigger 33 of the trigger body 24 in the sealed chamber 75 may be pulled freely. If this trigger 33 is pulled and then released, the match head composition 8 applied to the holder 9 secured to the controlling rod 6 will be rubbed against the abrasive agent on the abrasive agent holder 12, and ignition will be caused due to the friction, and

thus the inflammable powder 2 will ignite so that the desired signal is obtained as in the embodiment as illustrated in Fig. 1.

In the present invention, as described above, the ignition is effected by merely operating a trigger so that the desired signals may be sent very easily, speedily and reliably. With the described construction, a desired firing may be effected rapidly and exactly, even under poor conditions. As a result, a device according to this invention is an extremely effective means for preventing accidents.

What I claim:

1. A signalling device comprising in combination: a tubular waterproof housing having a combustible end portion, said housing defining an ignition chamber at least partly enclosed by said combustible end portion, a storage chamber accommodating inflammable powder and a passage extending through said storage chamber and communicating with said ignition chamber, a hollow grip member having an opening, a sleeve rotatably surrounding said grip member, said sleeve having an opening, a manually operable trigger member pivotally arranged within said hollow grip member, spring means bearing against said trigger member, a rod member secured to said trigger member and extending through said passage, said rod member having a portion comprising ignitable material, and a member having an abrasive surface mounted on the wall of said passage near said ignition chamber, said trigger member being capable of tensioning said spring means and releasing said spring means thereby causing said portion of said rod comprising ignitable material to rub against said abrasive surface.

2. In a signaling device as claimed in claim 1, cover means for closing said opening of said grip member and said opening of said sleeve, said means being capable of being broken prior to actuating said manually operable trigger member.
